(57) **CLAIM**

The ornamental design for a chair leg cover, as shown and described.

DESCRIPTION

FIG. 1 is a front elevational view of a chair leg cover showing my new design;

FIG. 2 is a left side view thereof;

FIG. 3 is a top plan view thereof;

FIG. 4 is a bottom plan view thereof; and,

FIG. 5 is a perspective view of a chair leg cover of FIG. 1. The oblique line shading used in the drawings indicates that the surfaces of the chair leg cover are transparent.
